UNITED STATES PATENT OFFICE.

IVAN H. STANT, OF CONNERSVILLE, INDIANA.

LOCK FOR RADIATOR CAPS.

Application filed July 5, 1924. Serial No. 724,499.

To all whom it may concern:

Be it known that I, IVAN H. STANT, a citizen of the United States, and a resident of Connersville, county of Fayette, and State 5 of Indiana, have invented a certain new and useful Lock for Radiator Caps; and I do hereby declare that the following is a full, clear, and exact description thereof, reference being had to the accompanying 10 drawings, in which like numerals refer to like parts.

This invention pertains to a lock device for radiator caps and mountings therefor, such as heat indicating devices, emblems and 15 the like, and more particularly to that type of lock which is attached to the underside of the cap or to the mounting extending therethrough and is insertable within the neck of the radiator, after which it is moved 20 to locking position.

One feature of the invention resides in the means for permitting the lock to be screwed onto the cap or mounting when turned to one position and thereafter be incapable of being unscrewed therefrom while 25 in the other or normal position of the cap when locked on the radiator.

The further feature of the invention resides in the means for maintaining the locking member in locking position under normal 30 conditions, but permitting its movement to inoperative position while being inserted in the radiator, said means being capable of releasing the locking member by means of proper application of a key in event that 35 it is necessary to remove the cap under unusual circumstances.

The full nature of the invention will be understood from the accompanying drawings and the following description and 40 claims:

In the drawings, Fig. 1 is a central vertical section through a portion of the radiator, its neck, locking device, radiator cap and 45 mounting with parts broken away. Fig. 2 is a view similar to Fig. 1, showing the locking device in side elevation and the cap unscrewed from the radiator for permitting the radiator to be filled. Fig. 3 is a section taken on the line 3-3 of Fig. 1.

In the drawings there is shown a radiator shell 10. The shell 10 is provided with the usual neck 11^a on which the radiator cap 12 is adapted to be screwed. Said radiator cap is provided with the mounting 13 which 50 may be in the form of a heat indicating de-

vice or ornamental mounting of any nature. Said mounting is secured to the cap by extending a screw threaded bolt projection 14 therethrough which is usually secured to 60 the underside of the cap by a bolt.

In place of the usual bolt, a locking device or anchor is provided which forms the subject of this invention, the same being connected to the bolt 14 of the member 13 65 by screwing thereon the internally threaded member 15 which is rotatably held in an annular groove 16 of the shell 17, said member being secured permanently therein, 70 but capable of being freely rotated.

The shell 17 is provided in one side thereof with a longitudinally extending bore 18, in which a locking pin 19 is positioned so as to readily slide therein. The connecting member 15 is also provided with a complementary bore 20 adapted to register therewith. By means of this arrangement, it will be readily observed that the member 15 may be freely rotated with respect to the shell 17 when turned in one position, and 80 when turned in the other position the pin 19 will move by gravity to a position where a portion thereof will extend into the bore 20 so as to lock the connecting member and shell and prevent the rotation of the former 85 with respect to the latter. This enables one to readily screw the connecting member 15 onto the threaded projection 14 when the cap and locking device are turned upside down, but when in normal position and the 90 locking member is in engagement with the radiator shell for locking the cap thereon, the free rotation of the connecting member 15 will prevent the unscrewing thereof.

In order that the locking device may be 95 unscrewed from the radiator cap when it is removed from the radiator after having been in use for a period of time, and in event the pin is rusted or corroded so as to stick within the bore, there is provided an opening 21 100 in the side of the shell communicating with the bore 18 and a downwardly extending reduced bore 22 in alignment therewith. After the device is locked in position, a lead shot may be wedged and forced into the opening 21 so as to close the same and also the communication between the bores 18 and 22. However, if the pin 19 becomes stuck in the bore, the lead shot may be readily melted 105 out and a small wire extended through the reduced bore 22 for forcing the pin into locking engagement.

The shell 17 is connected with a downwardly extending stem 23 by a ball and socket joint connection comprising the ball or head 24 connected with the stem 23 having a reduced neck portion 25, the socket comprising the lower portion of the shell which is reduced, and the inwardly extending annular flange portions 26. It will be noted that the reduced portion of the shell 10 is provided with a plurality of ports 27 therein for freely permitting the heat from the radiator to pass into the shell for effecting a heat indicating device.

The stem 23 has the lower portion thereof 15 hollow or bored out, and is provided with bifurcated ends 28 between which an anchor member 29 is pivotally secured by a rivet 30, the anchor member having laterally-extending arms on either side of the stem 23 20 so formed as to engage the underside of the radiator neck 11^a and prevent the removal thereof when in horizontal position, the same being capable of insertion or removal when moved about the pivotal connection 30 to a more vertical position.

For locking the anchor member in a horizontal or locking position, the same is provided with an upwardly extending central portion having a substantially flat surface 31 adapted to be engaged by a locking pin 32 in such manner as to prevent its movement about the pivotal mounting 30, when said pin is held in engagement with said surface 31. The pin 32 which lies in the bore, is provided on its upper end with a tapered or angular surface 33 which may be engaged by a screw threaded plug 34 which is screwed into the side of the stem for the purpose of holding and locking the pin 32 40 against the surface 31 for preventing movement of the anchor member 29. The plug 34 is provided with a hexagonal key-receiving recess 35 in its head for receiving a key 36.

45 After the locking device has been connected with the radiator cap, as above described, the anchor member 29 is moved to an angular position to permit its insertion through the radiator neck, after which it is forced to a horizontal locking position by a suitable tool. The plug 34 is then screwed into place for locking the pin 32. For locking the anchor member 29 in substantially horizontal position, it is tightened in place 50 by the wrench or tool 36, after which a lead shot may be forced into the recess 35 for preventing engagement with the plug and its removal from locking position. The locking device is so constructed that upon 55 unscrewing the cap from the radiator, it may be drawn upwardly until the locking member engages the bottom of the radiator neck, which will permit the shell and cap to turn partially over the side of the neck by 60 reason of the ball and socket joint so that

the radiator may be filled with water. There is, therefore, no occasion to remove the device excepting for unusual circumstances, in which event, it may be partially withdrawn and heat applied to the lead shot 70 so as to cause the melting of the same, whereby it will run out of the recess 35 and permit the wrench 36 to be engaged therein for unscrewing the locking plug 34. With the locking plug out of engagement with the 75 pin 32, a suitable tool may be used to move the anchor member 29 into such position as to permit the removal of the device from the radiator.

The invention claimed is:

1. In a lock of the character described adapted for attachment to a radiator cap comprising a hollow stem, means for connecting said stem to said cap, an anchor member pivotally connected to the lower end 80 of said stem, a pin slidably mounted in said hollow stem in position to have one end in engagement with said anchor member, and a plug having a recessed head for receiving a tool adapted to be screwed into 85 said stem in engagement with the other end of said pin for maintaining it in locking engagement with said anchor member.

2. In a lock of the character described adapted for attachment to a radiator cap comprising a hollow stem, means for connecting said stem to said cap, a cross bar pivoted to said stem and having an ear extending therein, said ear having a substantially flat surface, a locking member associated with said stem and positioned to engage the said flat ear for maintaining said cross bar in locking position, and a locking member positioned in said stem to engage 95 said locking pin and maintain it in locking 100 engagement.

3. In a lock of the character described adapted for attachment to a radiator cap comprising a stem, means for connecting said stem to said cap, said stem having slots located at the lower end thereof and on opposite sides, a cross bar pivotally connected to the lower end of said stem and located in said slots, said cross bar having an ear 110 extending into the shell and movable in said slots, said ear having a substantially flat surface, a locking pin associated with said stem in position to engage the flat surface of said cross bar for holding it in locking 115 position, the cross bar being pivoted to the stem at a point below said ear, and a locking member positioned in said stem to engage said locking pin and maintain it in locking 120 engagement.

4. In a lock of the character described adapted for attachment to a radiator cap comprising a stem, locking means mounted on said stem, connecting shell for connecting said stem with said cap, a nut rotatably mounted in said connecting shell, said shell 125 130

being provided with a concealed passage having one end communicating with said nut and the other end reduced, and a locking pin slidably mounted in said passage in 5 position to engage said nut and prevent its rotation when said shell is inverted and slide out of engagement with said nut permitting its rotation when said shell is in normal position, said concealed passage being provided with a radial passage connecting 10 therewith and the periphery of said shell for receiving a sealing substance for closing the passage against manual manipulation of said pin, and permitting said passage to be opened for manual manipulation of said pin 15 when said substance is removed, substantially as shown and described.

In witness whereof, I have hereunto affixed my signature.

IVAN H. STANT.
